COMBINED AMPLIFIER CASSETTE TAPE RECORDER

Takeyoshi Kawano, Osaka, Japan, assignor to Matsushita Electric Industrial Co., Ltd., Osaka, Japan

Filed Aug. 4, 1971, Ser. No. 169,152

Term of patent 14 years

Int. Cl. D14—03

U.S. Cl. D26—14 B

FIG. 1

FIG. 2

FIG. 3

FIG. 1 is a top, front perspective view of a combined amplifier cassette tape recorder incorporating my new design;

FIG. 2 is a rear, bottom perspective view thereof, from the opposite side to that of FIG. 1; and

FIG. 3 is a top, front perspective view of another embodiment incorporating my new design, the rear, bottom view from the opposite side being identical to that illustrated in FIG. 2.

Portions of the drawing figures are shaded to indicate contrast in appearance, and portions are diagonally inclined to indicate transparency.

I claim:

The ornamental design for a combined amplifier cassette tape recorder, as shown and described.
